CLAIM

The ornamental design for a rectangular dispensing container, as shown and described.

DESCRIPTION

FIG. 1 is a front elevational view of a rectangular dispensing container according to our new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front elevational view of a second embodiment of a rectangular dispensing container according to our new design, wherein the shading shows a contrasting color.

FIG. 8 is a rear elevational view of FIG. 7.

FIG. 9 is a left side elevational view of FIG. 7.

FIG. 10 is a right side elevational view of FIG. 7.

FIG. 11 is a top plan view of FIG. 7.

FIG. 12 is a bottom plan view of FIG. 7.

FIG. 13 is a front elevational view of a third embodiment of a rectangular dispensing container according to our new design.

FIG. 14 is a rear elevational view of FIG. 13.

FIG. 15 is a left side elevational view of FIG. 13.

FIG. 16 is a right side elevational view of FIG. 13.

FIG. 17 is a top plan view of FIG. 13; and,

FIG. 18 is a bottom plan view of FIG. 13.
